UNITED STATES PATENT OFFICE.

AIMEE HONNARD ALTFULDISCH, OF CAIRO, ILLINOIS.

EMBROIDERY-FRAME.

1,077,211.

Specification of Letters Patent.

Patented Oct. 28, 1913.

Application filed December 2, 1912. Serial No. 734,568.

To all whom it may concern:

Be it known that I, AIMEE H. ALTFULDISCH, citizen of the United States, residing at Cairo, in the county of Alexander and State of Illinois, have invented certain new and useful Improvements in Embroidery-Frames, of which the following is a specification.

My present invention relates to embroidery frames and more particularly to the type of embroidery frame set forth in my pending application filed June 27, 1910, and the object of my invention is to provide an expandible, fabric holding frame swingingly mounted upon a vertical supporting frame in such a manner that it may be readily adjusted for convenient use.

A further object of my invention is to provide a novel form of swinging connection between the fabric carrying frame and the supporting frame, permitting the former to be swung at any desired angle with respect to the latter and so arranged as to be always held in adjusted position, no tightening of bolts or other fastening devices being required.

A further object of my invention is to provide a vertical supporting frame having laterally directed feet, which, when the frame is not in use, may be swung to lie in a plane with the frame and still support the same, permitting the positioning of the frame against a wall and out of the way.

A still further object of my invention is to provide a fabric carrying frame and supporting frame so constructed that the frames may not only be separated from each other, but that the members going to make up each of the frames may be readily separated from each other to permit the packing of the entire device in knocked down condition for ready shipment. And a still further object of my invention is to construct a supporting frame including standards having supporting feet at their lower ends and supporting heads at their upper ends, the feet and heads being so formed that the supporting standards may be removed therefrom and the heads attached directly to the feet to support the fabric holding frame in but a slightly elevated position, thus permitting

the positioning of the entire device upon a table or bed.

With these and other objects in view, my invention will be more fully described, illustrated in the accompanying drawings, and then specifically pointed out in the claim which is attached to and forms a part of this application.

In the drawings: Figure 1 is a perspective view of my improved embroidery frame in use, showing a fabric stretched thereon; Fig. 2 is a side elevation of the fabric supporting frame mounted directly upon the supporting feet, the standards in this case being removed and the heads carrying the fabric frame being connected directly with the feet; Fig. 3 is a transverse sectional view of the structure shown in Fig. 1, parts being shown in section to more clearly illustrate certain details of construction; Fig. 4 is a side elevation of the device, showing the fabric holding frame swung into vertical position and the supporting feet turned in such a manner that the entire frame may be positioned against a wall to occupy but little space; Fig. 5 is a detail sectional view, showing the manner of mounting the fabric holding frame upon the supporting heads of the vertical frame; Fig. 6 is a fragmentary sectional view illustrating the manner in which the spacer bar connecting the standards is detachably secured in place.

Corresponding and like parts are referred to in the following description and indicated in all the views of the drawings by the same reference characters.

In the drawings, which illustrate the preferred embodiment of my invention, 10 designates a vertical supporting frame and 11 an expandible fabric stretching frame swingingly mounted upon the supporting frame. The supporting frame includes spaced apart, vertical standards 12 and 13 which may be of any preferred size and shape and which may be carved or otherwise ornamented, if desired, these standards being usually made of wood in order to provide as light a structure as possible. Each of these standards, as best shown in Fig. 3 100 of the drawings, is provided at its lower end with a reduced, cylindrical extension 14

which seats in a cylindrical socket 15 formed in the central upper portion of an arcuately shaped supporting foot 16. These supporting standards are connected adjacent their 5 lower ends and held in proper spaced relation by a spacer bar 17 also formed of wood and provided at its ends with reduced cylindrical extensions 18 which, as best shown in Fig. 6 of the drawings, seat in 10 cylindrical sockets 19 formed in the lower portions of the standards 12 and 13.

The ends of the spacer bar 17 are provided with centrally formed longitudinally extending bores 20 and the socketed portions of the supporting standards are provided with transverse bores 21 in alignment with the bores 20 when the spacer bar is in place. The end portions of the spacer bar are also provided with radially extending recesses 22 adapted to receive internally threaded nuts 23 in such a manner as to position them in engagement with the threaded terminals of bolts 24 passed through the bores 21 and into the bores 20, 25 the nuts being so proportioned as to be held against longitudinal movement as shown in Fig. 6. These nuts are properly positioned before the parts are assembled and are preferably hidden from view and secured in 30 place by plugs 25 inserted in the outer ends of the nut receiving recesses, these plugs being formed of the same kind of wood as the spacer bar and having their exterior faces shaped to conform to the surface of 35 the spacer bar. The bolts 24 are each provided with a spherical head 26 having transversely formed key receiving openings 27 by means of which they may be turned to firmly lock the parts in place.

40 Mounted upon the upper ends of the supporting standards are frame supporting heads 28 and 29, these heads being also formed of wood and provided at their lower ends with cylindrical extensions 30 seating 45 in cylindrical sockets 31 formed in the upper ends of the standards. Set screws 32 are threaded in the standards to engage by their inner ends against the cylindrical portions 30 of the heads and lock the same in 50 position. The heads 28 and 29 are preferably comparatively low, formed to combine with the standards and so shaped that when in place they appear as part of the standards. The upper ends of the heads are 55 bifurcated as at 33 to form spaced ears 34 and 35, the inner faces of the ears formed by the bifurcating of the ends converging toward their upper ends to form in effect a wedge-shaped slot, as best shown in Fig. 5 60 of the drawings.

The fabric stretching frame, previously designated as a whole by the numeral 11, includes side members 36 and 37 formed centrally with downwardly depending ears 38

adapted for engagement between the spaced 65 ears 34 and 35 of the standard heads, these ears, as shown in Fig. 5 of the drawings, being wedge-shaped to bear by their faces against the converging faces of the ears 34 and 35. Bolts 39 are passed through alined 70 openings formed in the ears 34, 35 and 36 and winged nuts 40 are threaded upon the bolts to frictionally clamp the ears 36 between the ears 34 and 35. By this construction the side members 36 and 37 of the fabric stretching frame are swingingly mounted 75 upon the supporting heads 28 and 29, respectively, and because of the engagement of the wedge-shaped ears 36 of the side members in the wedge-shaped slots of the 80 heads, these side members may be swung at any desired angle to the standards without the necessity of first loosening the nuts 40 and when swung to any desired position, will be firmly held in place. The end portions of these side members are reduced and threaded as shown at 41 to receive adjusting nuts 42 in the form of relatively large disks which may be readily turned by hand. The fabric supporting frame also includes fabric holding bars 43 and 44, the ends of which are provided with transverse bores by means of which said fabric holding bars may be mounted upon the ends of the side members or spacer bars 36 and 37, these 95 bores being of such diameter as to permit the ready movement of the bars over the threaded portions of said members. These fabric supporting bars are mounted upon the ends of the side members 36 and 37 exterior to the nuts 42 and it will therefore be seen that the fabric supporting bars may be forced away from each other by a suitable turning of the nuts to stretch a fabric secured thereon.

100 The intermediate portions of the bars 43 and 44 are preferably cylindrical in shape and covered with fabric 45 as shown in Fig. 3 of the drawings, this fabric covering preferably being formed of flannel, felt or other soft material and being preferably secured upon the bars in such a manner as to be held against all turning movement thereon and the fabric to be worked on is secured by its ends to the bars 43 and 44 by sewing, 110 pinning or otherwise securing it to the fabric covering 45 of the bars.

115 The sockets 15 formed in the supporting feet of the vertical frame are equal in diameter to the sockets 31 formed in the upper ends of the standards and it will therefore be apparent that inasmuch as the standards are readily detachable from the feet and the heads from the standards, that the standards may be removed from the feet and 120 heads, and the reduced extensions 30 of the heads seated directly in the sockets 15 of the feet, if desired. Because of this con-

struction, the fabric holding frame may be supported above a table or bed in a comparatively low position and by the employment of the supporting feet normally used 5 in connection with the vertical standards.

In operation, the supporting frame and fabric carrying frame are assembled and positioned as shown in Fig. 1 of the drawings and the ends of the fabric fastened in 10 any suitable manner to the fabric covering of the bars 43 and 44, the nuts 42 being turned toward the center of the side member to permit the movement of the bars 43 and 44 toward each other and therefore 15 provide for the ready fastening of the fabric in place. When the fabric has been secured in place, the nuts 42 are turned in the reverse direction to force the bars 43 and 44 away from each other and so stretch and 20 hold the fabric, indicated by the numeral 46 in place. Because of the fact that the side members 36 and 37 are swingingly mounted upon the supporting frame, the fabric carrying frame may be readily swung 25 to any desired angle convenient for the sewing, embroidering or quilting operation to be performed thereon and if desired may be swung in such a manner as to permit the person operating upon the fabric to 30 view either the upper or lower side thereof.

Inasmuch as the fabric supporting frame may be readily detached from the vertical frame by the removal of the bolts 39, it will be apparent that a number of fabric 35 supporting frames of various sizes may be employed in connection with a single supporting frame and that these frames may be readily removed from or attached to the supporting frame even though the fabric is 40 stretched thereon.

When the device is not in use, the supporting feet 16 may be swung at right angles to lie in the same plane with the supporting standards and spacer bar 17 45 and the fabric carrying frame may be swung to vertical position to permit the placing of the entire device against a wall and out of the way, as clearly shown in Fig. 4 of the drawings. This operation 50 may be performed while the fabric is still upon the frame or when the frame is empty. Under the latter condition, the fabric supporting bars 43 and 44 may be either removed completely from the frame or that 55 bar which would ordinarily be upon the lower ends of the side members may be removed and positioned upon the opposite ends of said members. It will also be apparent that if this latter method is adopted 60 that the adjusting nuts upon the lower ends of the side members may be removed and applied to the opposite ends of said members to secure the fabric holding bars in place. If the bars are to be locked in place

by means of the nuts in this manner, they 65 may, if preferred, be mounted upon the lower ends of the side members. As these various methods of positioning the bars and nuts when the device is not in use will be clearly understood, it has been thought unnecessary to illustrate them in the drawings. 70

If the fabric to be worked upon is to be placed over a table or bed, the feet are removed from the supporting standards 12 and 13 and the heads 28 and 29, together 75 with the fabric supporting frame are removed from the standards and applied directly to the feet as illustrated in Fig. 2 of the drawings. With this construction, it will be apparent that not only side members of any length but also fabric supporting members of any length may be employed as the feet and heads are not connected to each other by a spacer bar. These same fabric supporting frame members may 80 be employed with the supporting standards, as well, by removing the bolts 24 and the spacer bar 17 when the supporting standards may be spaced at any desired distance from 85 each other. 90

If the frame is to be stored for any length of time or packed for shipment, it may be completely taken apart by removing the feet and spacer bar from the standards, removing the heads from the standards and 95 from the fabric supporting frame and by removing the fabric carrying bars and nuts from the side members of the fabric carrying frame. In this knocked down condition, the entire device may be packed in a relatively small space and in such a manner 100 that it will not be broken during transportation.

Although I have illustrated and described the device as employed for stretching and 105 supporting a fabric for embroidering purposes, it will of course be understood that the device may be employed as a quilting frame or as a drying frame for stretching lace curtains or other delicate fabrics after 110 washing. In fact, it may be employed under all circumstances in which it is desirable to stretch or hold in stretched position, any kind of a fabric.

It will of course be understood that 115 although I have illustrated and described the device and all of its details of construction, I do not wish in any way to limit myself to these specific details as minor changes in construction, within the scope 120 of the appended claim, may be made at any time, if desired, without in the slightest degree departing from the spirit of my invention.

Having thus described the invention, 125 what is claimed as new is:

An embroidery frame including spaced standards provided in their upper ends with

sockets, heads having extensions seating in the sockets, and spaced ears with upwardly converging inner faces, a fabric stretching frame having downwardly depending ears 5 engaging between the spaced ears of the heads, the outer faces of the frame ears converging upwardly to correspond to the inner faces of the first mentioned ears, bolts passed through the head ears and frame

ears to pivot the frame on the heads, and 10 clamping nuts threaded upon said bolts.

In testimony whereof I affix my signature in presence of two witnesses.

[L.s.] AIMEE HONNARD ALTFULDISCH.
